UNITED STATES PATENT OFFICE.

JOHN C. NOBLES, OF ATLANTIC HIGHLANDS, NEW JERSEY.

DESIGN FOR A BLUING-STRAINER.

SPECIFICATION forming part of Design No. 15,979, dated March 17, 1885.

Application filed February 7, 1885. Term of patent 7 years.

To all whom it may concern:

Be it known that I, JOHN C. NOBLES, a citizen of the United States, residing at Atlantic Highlands, in the county of Monmouth and State of New Jersey, have invented certain new and useful Designs for Bluing Implements; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention, and is a perspective view. Fig. 2 is a view of the under side.

This design has relation to stir-about bluing-strainers, for use in the laundry; and it 20 consists in the novel form and configuration of the instrument, as hereinafter shown and described.

In the accompanying drawings the design is illustrated, consisting of the bulb portion A, of spherical form, having the bead B extending around its middle portion. The top C of the bulb is in neck form and concave, and the loop-handle D is shown with its arms E extending out of the recess in said top, and twisted together at F.

Having described this design, what I claim, and desire to secure by Letters Patent, is—

The design for a bluing-strainer, consisting of the beaded bulb and loop-handle having its branches extending out of the concave top 35 of the bulb and twisted together at F, as shown and described.

In testimony whereof I affix my signature in presence of two witnesses.

JOHN C. NOBLES.
